ILLUMINABLE DISPLAY APPARATUS FOR TRANSPARENCIES OR SIMILAR ARTICLE

Jerome J. Lieberman and Leon D. Lieberman, both of 5768 W. Adams Blvd., Los Angeles, Calif. 90016

Filed Oct. 21, 1966, Ser. No. 4,364

Term of patent 14 years

(Cl. D61—1)

FIGURE 1 is a front perspective view of an illuminable display apparatus for transparencies or similar article, showing our new design;

The right side of the apparatus, not shown, is a mirror image of the left side, while the bottom, not shown, is plain and unornamented. The drawing figures are stippled to indicate contrast in appearance, and portions thereof are diagonally lined to indicate transparency.

We claim:

The ornamental design for an illuminable display apparatus for transparencies or similar article, substantially as shown and described.
